METHOD OF MAKING TRANSDUCER CORES

William E. Pollock, Sun Valley, Calif., assignor to Librascope, Incorporated, Glendale, Calif., a corporation of California

Application June 3, 1953, Serial No. 359,251

5 Claims. (Cl. 29—155.5)

This invention relates to the manufacture of cores for magnetic transducers, and particularly to means and a method for producing a fine gap in a sintered toroidal core.

In the electromagnetic art as applied to computing devices, the recording or reading of information is frequently accomplished by the use of a small toroidal electro-magnetic transducer head. This head consists of a toroidal core with a gap extending radially across one point in its periphery, and having windings disposed thereabout for the passage of current. The magnetic field may be distorted outwardly at the gap portion of the toroid, and it is this extending field which cooperates with the data storage medium in recording or picking up information.

The toroid itself is formed of material having high magnetic permeability, with low eddy current and hysteresis loss. It has been found that a core made by compressing material such as powdered manganese zinc ferrites at a temperature sufficient to cause sintering will have a hard, rigid structure which possesses such characteristics in a high degree.

Since the sintered ferrite is extremely hard, the slot has had to be cut in the past by means such as a diamond saw. The effectiveness of the head in recording a large number of bits of information in a small space is inversely related to the width of the gap in the toroid. The best gaps produced by diamond sawing have been of the order of one to two thousandths of an inch.

With the present invention satisfactory gaps have been produced having a width of the order of one ten-thousandths of an inch, and the gap width may be fixed at any value up to about five ten-thousandths if desired.

The fine gap is produced by the method of applying controlled stretching force in a direction tangential to the toroid at a point at which the cross-sectional area of the toroid has been previously reduced, and removing the force at the instant the fracture occurs.

It is well known that glass and ceramic articles, which have many physical characteristics in common with sintered materials, may be fractured along a desired line by scribing the surface with a diamond point, and applying a bending force transversely of the inscribed line. However, it has never before been appreciated that controlled tension might be used to separate parts of a closed figure of such rigid or semi-rigid material, such as a toroid, without fracturing it at more than one location.

A fracture at a single point may be produced, according to the present invention, with the aid of a fixture which will impart sufficient tangential tension to break the core where the cross-section has been reduced, but which will exert no further force, once the toroid has fractured at the single desired location.

The object of the invention is thus primarily to improve the manufacture of toroidal cores of sintered materials.

Another object of the invention is to provide means

2

and a method for producing a controlled fine gap in such cores.

A further object is the production of sintered toroidal cores with magnetic gaps of a much smaller order of magnitude than has hitherto been possible.

Yet another object is rapid and inexpensive production of sintered toroidal cores having extremely fine but accurately controlled gaps.

These and other objects may be better understood from 10 the description following when read in conjunction with the drawings, in which:

Fig. 1 is a front elevational view of a fixture for fracturing a core in accordance with the method of the invention, with a dotted showing of a core in position 15 on the fixture ready for the fracturing operation;

Fig. 2 is a side view of the fixture, taken as indicated by line 2—2 of Fig. 1;

Fig. 3 is a fragmentary sectional view taken as indicated by line 3—3 of Fig. 1; and

Fig. 4 is a fragmentary sectional view taken as indicated by line 4—4 of Fig. 1.

Fig. 5 is a detailed view of a core having a gap produced by the method of the invention.

Fig. 6 is a detailed view of an alternative form of fixture for fracturing a core, shown in position to be treated.

The method here disclosed consists in reducing the cross-sectional area of the core at the desired gap location to about one-fourth its extent elsewhere by notching 30 its internal periphery in a deep V, and scribing the exterior exactly opposite the apex of the V cut, as preliminary steps.

The core is then clamped radially on both sides of 35 the V, and a stretching force applied tangentially of the core at the notched portion.

Application of the stretching force is continued until the core fractures, and is then removed. The fracture may later be spread to permit the insertion of a thin shim of silver or equivalent material, but in no case should it be permitted to a degree which will cause a second fracture of the core.

A preferred form of fixture adapted to carry out the method has been shown in the Figs. 1—4.

The fixture consists of a body portion 1 formed from a substantially rectangular strip of readily machined material such as brass.

A cross-bore 2 is formed thru the narrower dimension of body 1, and a slot 4 cut from the bore toward the 50 adjacent end 5 of the body. A portion of the body 1 is reduced in width near the end 5. The slot 4 and the reduced width body portion defines legs 6 and 7. A threaded bore 9 is formed in leg 7 near end 5 transversely of slot 4 and normal to the axis of bore 2. A tension screw 10 is inserted in the threaded bore 9, in position 55 to bear against leg 6.

The cross-bore 2 is of substantial size in relation to the body 1 and legs 6 and 7. Hence, when tension screw 10 is tightened against leg 6, the legs 6 and 7 will remain straight, but will be spread apart about the bore 2 as a center.

The stretching force is applied to the toroid by means of bosses 11 and 12 formed integrally with legs 6 and 7 respectively, and extending therefrom parallel to the axis of bore 2 far enough to provide a firm seat for the core 60 14 in which the gap is to be formed.

The core 14 is prepared by rounding off any sharp corners or extrusions remaining from the molding and sintering operation, and providing a V notch 15 in its inner periphery, having an included angle of about 60°, either in the molding of the core or by cutting the same with a diamond hone. The angle selected is one which

will concentrate the magnetic field at the gap, so that the lines of force will tend to pass through the magnetic data storage medium. Other angles up to about 90° have also been found satisfactory. The notch should be deep enough so that substantially only one-fourth of the radial extent of the toroid remains. The thickness at the bottom of the notch would be about .025" in a typical embodiment in which the toroid has an outside diameter of 1/2" and a toroidal cross-section approximately .093" square. The toroid 14 is then scribed on its external periphery opposite the bottom of the notch 15 with a sharp diamond or carboloy point, and may be coated with lacquer to prevent the dislodging of small particles adjacent the scribed line during the fracturing process.

Bosses 11 and 12 have engaging faces 16 and 17 formed thereon including a corresponding 60° angle. In case it is desired to vary the included notch angle, a fixture must be used having an angle between the engaging faces corresponding to the newly selected notch angle.

Clamping abutments 19 and 20 are formed terminally of legs 6 and 7, respectively, extending in the same direction from the legs 6 and 7 as do the bosses 11 and 12. Threaded bores 21 and 22 are formed in clamping abutments 19 and 20 with axes intersecting at the position which will be occupied by the center of core 14. Clamping screws 24 and 25 are disposed in bores 21 and 22, and arranged to engage the periphery of core 14 on opposite sides of the intended gap. Screws 24 and 25 will hence exert their clamping effect radially of a toroidal core emplaced on the bosses 11 and 12.

The various elements of the fixture shown in the figures are so spaced that when a core is placed on the bosses 11 and 12, and clamping screws 24 and 25 are tightened, the tightening of tension screw 10 against leg 6 will create stress in the core in a direction substantially tangent to the center line of the core at the notched portion. The force will also be substantially uniform throughout the reduced cross-section of the core. Screw 10 is turned until the reduced cross-section portion of core 14 has fractured at 26, as determined by visual observation through a microscope, or equivalent means. Application of spreading force is then stopped.

The core may be later spread to allow the insertion of a sheet 27 of silver foil or equivalent material, which is usually of the order of .0001" thick. The core will fracture opposite the gap if it is spread excessively, however, and care should be taken to limit the distortion to the least amount which will permit the ready insertion of the foil. In cores of the dimensions set forth above, a second fracture will occur diametrically opposite the first, if the gap is spread to about .002".

When the force tending to spread the core is removed, the core will spring back and hold the foil 7 firmly in place. The foil 27 will deform to mate with any surface irregularities of the core at the fracture 26 and the gap will then be of known length. Any excess foil protruding beyond the core should be trimmed away.

By further working of the fracture gap produced in the manner described herein, it is possible to produce gaps of any desired width which are still narrower than any gap heretofore produced by sawing of the toroidal core material.

A gap slightly wider than that produced by fracture of the toroid as herein described may be produced by first spreading the gap produced by fracture sufficiently to admit a strip of foil of the order of .0001 of an inch in thickness coated with a lapping material including diamond dust or the like, and then lapping the walls of the fracture by reciprocating the coated foil in contact with them. This operation also frees the walls from any irregularities incident to fracturing of the material. After lapping the walls of the fracture to the desired extent, the coated foil is removed and a foil shim of the thickness of the desired gap is inserted; after which the tension employed to spread the gap is relieved, so that the resiliency

of the material of the toroid, slight as it is, will cause the toroid to clamp the sides of the gap tightly against the foil shim.

For gaps slightly wider than can be conveniently produced by such lapping, a saw of the order of .0005 of an inch in thickness may be used in conjunction with diamond dust or the like to widen the gap and free the walls of the fracture from any incidental irregularities. Gaps narrower than the thickness of such a saw blade may be produced by first spreading the gap produced by fracture sufficiently to permit a sawed slot to be started with such a saw and only partially relaxing the force spreading the gap as the sawing operation progresses. Then, when the saw has passed completely through the fractured area and has been removed therefrom, a foil shim of the order of .00025 of an inch in thickness may be inserted in the slot, and upon complete relaxation of the force tending to spread the gap, the resiliency of the toroid material, slight as it is, will cause the toroid to clamp the sides of the gap tightly against the foil shim, leaving a gap of a width of .00025 of an inch, or less than that of the saw used.

A still wider gap may be produced by an operation identical to that just described except in that the force tending to spread the gap is completely relaxed during the sawing operation. A gap produced in this manner will be of the order of the thickness of the saw blade and will be less than could have been produced by sawing an unfractured toroid with a saw of the same thickness. Gaps produced by sawing in the manner herein described will also be completed in a matter of minutes as compared with a matter of hours of required sawing time for unfractured toroids of the same material.

The outer periphery of the core is next ground away sufficiently across the gap to slightly flatten the surface, and remove any irregularities due to the scribing operation. This flattening is shown to an exaggerated scale in Fig. 5 at 8, and assists in securing the close spacing to the magnetic medium required. The core is now ready to have coil windings applied, and to be mounted in a head unit for use.

As an alternative to the use of the fixture shown in Figs. 1-4, the fracture may be produced by forcing the prepared core axially onto a suitably tapered pin. If the inside diameter of the core has been ground to be truly cylindrical, a relatively uniform application of force is thus obtained about the inner periphery of the core. The force tending to move the core toward the pin end of larger diameter is stopped immediately on fracture. The other steps in the process are the same as those described supra.

Fig. 6 shows a core 14 in place on a tapered pin 29. The taper of pin 29 has been exaggerated in the drawing for purposes of illustration. It may conveniently have a taper of .001" per inch of length in practice. The pin 29 is clamped in a suitable vise or holder and means such as a length of cylindrical tubing may be used to apply force uniformly to the toroid 14. The vise and the tubing are conventional, and neither is shown in the drawing. The direction of the applied force should be parallel to the axis of the pin 29, to avoid stressing the toroid unevenly.

I claim:

1. A method of producing a gap in a transducer core having a toroidal configuration such as a magnetic core, comprising the steps of grooving the core at a line along which the gap is to be produced and applying a stressing force on said core to separate the core at said line until the core fractures at said line, arresting the application of such stressing force at the instant of said fracture at said line whereby the core is prevented from breaking other than along said line, spreading the gap slightly and inserting a dimensioned shim in said gap, and releasing said stressing force.

2. A method of producing a gap in a transducer core having a toroidal configuration such as a magnetic core,

comprising the steps of grooving the core at a line along which the gap is to be produced and applying a stressing force on said core to separate the core until it fractures at said line, arresting the application of such stressing force at the instant of fracture whereby the core is prevented from breaking other than along said line, spreading the gap slightly, inserting an abrasive-charged foil strip into said gap, lapping the opposite faces of said core at said fracture, removing said abrasive-charged strip, inserting a dimensioned shim in said gap and releasing said stressing force.

3. A method of producing a gap in a transducer core having a toroidal configuration such as a magnetic core, comprising the steps of grooving the core at a line along which the gap is to be produced and applying a stressing force on said core to separate the core until the core fractures at said line, arresting the application of such stressing force at the instant of fracture whereby the core is prevented from breaking other than along said line, spreading the gap slightly, inserting an abrasive-charged foil strip into the gap, releasing the stressing force in said core, reciprocating said strip to lap the opposite fractured surfaces in said core, again spreading said gap, removing said abrasive-charged foil from said gap, inserting a dimensioned shim in said gap, and releasing said stressing force.

4. A method of producing a gap in a transducer core having a toroidal configuration such as a magnetic core, comprising the steps of grooving the core at a line along which the gap is to be produced and applying a stressing force on said core to separate the core until the core fractures at said line, arresting the application of such stressing force at the instant of said fracture whereby the core is prevented from breaking other than along said line, spreading

the gap slightly to receive an abrasive-charged saw blade, partially releasing the stressing force on said core, reciprocating said blade to cut away irregularities in the opposed fractured surfaces of said core, removing said blade from said gap, inserting a dimensioned shim in said gap, and releasing said stressing force.

5. A method of producing a gap in a transducer core having a toroidal configuration such as a magnetic core, wherein said gap is smaller in length than the thickness of the tool used for cutting, comprising the steps of grooving the core at a line along which the gap is to be produced, applying a stressing force on said core to separate the core at said line until the core fractures, arresting the application of such stressing force on said core at the instant of fracture whereby the core is prevented from breaking other than along said line, spreading the gap to receive an abrasive-charged saw blade, reciprocating said blade to smooth irregularities in the opposed fractured surfaces of said core, removing said blade from said gap, inserting a shim of thickness less than that of said blade in said gap, and releasing said stressing force.
